UNITED STATES PATENT OFFICE.

CARL R. WASER, OF PHILADELPHIA, PENNSYLVANIA, ASSIGNOR TO PRECISION THERMOMETER & INSTRUMENT COMPANY, OF PHILADELPHIA, PENNSYLVANIA, A CORPORATION OF PENNSYLVANIA.

SPHYGMOMANOMETER.

1,164,896.

Specification of Letters Patent. Patented Dec. 21, 1915.

Application filed September 19, 1914. Serial No. 862,444.

To all whom it may concern:

Be it known that I, CARL R. WASER, a citizen of the United States, residing in the city of Philadelphia, county of Philadelphia, and State of Pennsylvania, have invented certain Improvements in Sphygmomanometers, of which the following is a specification.

This invention is a sphygmomanometer of improved construction designed to provide an instrument of superior characteristics particularly in the matters of accuracy, simplicity, compactness and stability.

The characteristic features of my invention are disclosed in the following description and the accompanying drawings in illustration thereof.

In the drawings, Figure 1 is a side elevation of an erected instrument embodying my improvements; Fig. 2 is a front elevation of the same; Fig. 3 is a side elevation of a broken section of the same with the parts partially collapsed; Fig. 4 is an enlarged sectional plan view of the collapsed instrument on the line 4—4 of Fig. 3; and Fig. 5 is a sectional view on the line 5—5 of Fig. 2.

The instrument, as illustrated in the drawings, comprises the case 1 having a lid 2 hinged by pintles 3, the case having a spring 4 fixed to its bottom at the rear end to engage a catch 5 on the lid to hold the latter in its elevated position, the lid being held in its closed position by the engagement of a catch 4' on the spring 4 with the catch 5' on the lid.

A metal cistern 6 and the glass tube 7 are connected by a metal base 8, in which they are set, and these parts are fixed to the interior face of the lid. The top of the cistern has fixed thereto a fixture 9 adapted for the engagement of a three way nipple 10 through which it is connected with the respective tubes 11 and 12 communicating with the pump 13 and cuff 14.

A bearing 15, fixed to the lid adjacent to the top of the tube or tube section 7, holds a cylindrical clip or seat 16 (provided with the fenestration 16') in which the top of the tube is fixed. The bearing also has fixed thereto the hinge knuckles 17 on oppo-

site sides of the top of the tube and the hinge knuckles 18 projecting inwardly into the recess 2' of the lid. A bearing 19 is provided with the hinge knuckles 20 connected with the knuckles 17 by the pintles 21, the bearing carrying the cylindrical seat or clip 22 (provided with the fenestration 22') in which is fixed the end of the tube or tube section 23 adapted to register with 55 and engage the end of the tube section 7. A bearing 24, fixed to the lid, is provided with springs 25 having inturned ends 25' for engaging the knuckles 20 and holding the tube 23 in registration and alinement 60 with the tube 7, the frictional engagement of the springs with the knuckles permitting the latter to be disengaged from the former by the application of sufficient pressure to the tube 23 in the operation of folding it 65 down within the limits of the lid 2.

A valve 26 is provided with the hinge knuckles 27 which are pivotally connected with the knuckles 18 by the pintle 28 on which is a coiled spring 29 having an end 29' anchored to the lid and an end 29'' impinging against the valve to automatically turn the latter down upon the end of the tube 7 when this is exposed by turning down the tube 23. An arm or finger 30 projects from the valve 26 and bears against the adjacent end of the tube 23 when the latter is folded down, the arm being elevated to automatically open the valve by the operation of lifting the tube 23.

A spring 43 fixed within the forward end of the case engages the arm 30 to hold the valve 26 securely against the end of the tube 7 when the lid is closed to prevent the possibility of the escape of mercury through 90 the opening of the valve.

Angular bearings 31 are fixed to the lid 2 and support a scale or scale section 32 provided with bearings 33 containing slots 33', screws 34 and 35 passing through the slots 95 into the bearings 31 to hold the bearings 33 while permitting limited movements thereof. A clamp 36 is mounted on the stud 35 and is adapted to be turned by the lever 37 to fix the scale section in position. 100 The scale section 32 is provided with a hinge knuckle 32' and a scale section 38 is pro-

vided with a hinge knuckle 38' connected with the knuckle 32' by a pintle 39, whereby the scale section 38 may be folded down against the section 32 or erected in registration and alinement therewith.

5 A loop or clip 40 fixed to the scale section 38 engages the tube 23 in relatively movable relation to compensate for the differences in their movements on their respective hinges.

10 The top of the tube 23 has a threaded ring 41 fixed thereon for the reception of a cap 42 containing an aperture 42', the cap being adapted for holding a wad or disk of cotton, porous skin or the like against the top of the tube to prevent the escape of mercury while permitting the passage of air.

15 Having described my invention, I claim:

20 1. A sphygmomanometer comprising a tube having sections, a hinge whereby one of said sections is adapted to be folded with reference to the other, and means comprising a device movable transversely to the plane of oscillation of the folding section for holding it in registration with the complementary section.

25 30 2. A sphygmomanometer comprising a tube having complementary sections, a hinge whereby one of said sections is adapted to be folded relatively to the other, and means comprising a spring adapted for engaging a hinge member of the folding section for holding it in registration with the other section.

35 40 45 3. A sphygmomanometer comprising a case having a lid, a fenestrated clip connected with said lid, said clip having a hinge knuckle fixed thereto, a tube section having an end set in said clip, a second fenestrated clip having a hinge knuckle connected to said hinge knuckle first named, a second tube section having an end fixed in the second named clip, and means comprising a spring engaging the knuckle of the second named clip for holding said second tube section in registration with said tube section first named.

50 55 60 4. A sphygmomanometer comprising a case having a lid, a fenestrated clip connected with said lid, said clip having a hinge knuckle thereon, a tube section having an end set in said clip, a second fenestrated clip having a hinge knuckle pivotally connected to said hinge knuckle first named, a second tube section having an end set in the second clip, and a spring fixed to said lid and adapted to engage the knuckle of said second clip to hold said second tube section in registration with the tube section first named.

65 5. A sphygmomanometer comprising a case having a lid, a clip with a hinge member fixed to said lid, a tube section having an end set in said clip, a second clip having a hinge member connected to said hinge member first named, a second tube section

having an end set in said second clip, and springs fixed to said lid on opposite sides of said tube sections whereby said second tube section is held in registration with said tube section first named.

70 6. A sphygmomanometer comprising a case having a lid containing a recess, a clip fixed to said lid and having a hinge member, a tube section having an end set in said clip, a second clip having a hinge member connected to said hinge member first named, and a valve having a hinge in said recess, said valve being adapted for closing the end of said tube section first named.

75 80 15 7. A sphygmomanometer comprising a case having a lid, a tube section fixed to said lid, a tube section hinged to said tube section first named, a valve for closing said tube section first named, and means in said case into engagement with which said valve is moved on closing said lid, whereby said valve is held in position closing said tube section first named.

85 90 95 8. A sphygmomanometer comprising a case having a lid, a tube section fixed to said lid, a complementary tube section hinged relatively to said tube section first named, a scale section, means comprising a clamp connected with said lid for holding said scale section in adjustable relation to said tube section first named, and a scale section hinged to said scale section first named.

95 100 105 9. A sphygmomanometer comprising a manometer tube, a scale for reading said tube, a transverse web fixed to said scale, a supporting device having a web parallel to said web first named, and means for clamping said webs together.

110 10. A sphygmomanometer comprising a case having a lid, a tube section fixed to said lid, a tube section hinged to said tube section first named, a scale section fixed to said lid, a scale section hinged to said scale section first named, and means for connecting said hinged tube and scale sections to permit one to move relatively to the other.

115 120 125 11. A sphygmomanometer comprising a casing having a lid, a tube section fixed to said lid, a spring fixed to said casing, a device fixed to said lid and engaging said spring for holding said lid in the open position, and a device fixed to said lid and engaging said spring for holding said lid in the closed position.

130 120 125 12. A sphygmomanometer comprising a casing having a lid, a tube section fixed to said lid, a spring having a head fixed to said casing, and a catch connected with said lid and adapted for engaging said head to hold said lid in the closed position.

135 125 130 13. A sphygmomanometer having a reading tube comprising two sections and means comprising a hinge for connecting said sections in flexible relation, said hinge having connected knuckles connected with an off-

set from the respective tube sections, in combination with a reading scale comprising two sections and means comprising a hinge for connecting the sections of said scale, 5 said hinge last named disposed between the complementary knuckles aforesaid.

In testimony whereof I have hereunto set

my name this 17th day of September, 1914, in the presence of the subscribing witnesses.

CARL R. WASER.
